UNITED STATES PATENT OFFICE

LAURENCE M. PERSONS, OF ST. LOUIS, MISSOURI, ASSIGNOR TO EMERSON ELECTRIC MANUFACTURING CO., OF ST. LOUIS, MISSOURI, A CORPORATION OF MISSOURI

FAN

Application filed August 16, 1929. Serial No. 386,398.

My invention relates to an improvement in ventilating systems and in fans operable in connection therewith. One object is to provide an improved drive which is adaptable, among other uses, to drive a duplex fan. Another object is the provision of an improved duplex fan. Another object is the provision of a ventilating system in which an improved duplex fan is associated with a duct or plurality of ducts, through which the fan is adapted to draw or drive air or gases or the like. A typical application of my invention is its use in connection with the supply of air for heating to a domestic furnace, the air, after it is heated, being returned to one or more points throughout a dwelling.

I illustrate my invention more or less diagrammatically in the accompanying drawings, wherein—

Figure 1 is a side elevation with parts in vertical section;

Figure 2 is an elevation of a motor on an enlarged scale, with parts in axial section; and

Figure 3 is a transverse section on the line 3—3 of Figure 2.

Like parts are indicated by like symbols throughout the specification and drawings.

Referring to the drawings, for example to Figure 1, A generally and diagrammatically indicates a furnace with the outer jacket A¹ and the heated air ducts A². A³ indicates a cold air return duct and A⁴ a passage adapted to connect the cold air or connection duct A⁸ with the furnace A.

B generally indicates a motor which is shown in Figure 1 as adjustably mounted upon the stem B¹, as by the sleeve B² and the adjusting or locking screw B³. The stem B¹ is shown in Figure 1 as projecting upwardly through the wall of the passage A⁴, being externally supported as upon the base B⁴.

Referring to Figures 2 and 3 which illustrate the structure in greater detail, C is the motor shaft which, it is understood, is rotated

in a constant direction of rotation. Mounted about it is the sleeve or extension C¹ which is locked thereto as by the screw C² passing through the collar C³. C⁴ is any suitable anti-friction member or washer the purpose for which will later appear. C⁵ indicates a head at the outer end of the sleeve C¹ spaced outwardly beyond the end of the stub shaft C. It is provided with a shoulder C⁶ and a seat portion C⁷, of less diameter than the shoulder, and indicated as generally cylindrical. The seat C⁷ is adapted to receive the inner ball race D which may be thrust against the shoulder C⁶, as by the lock nuts or locking members C⁸, screwthreaded upon the extension C⁹ of the head C⁵. This extension is axially apertured or indented as at C¹⁰ the purpose of which aperture will later appear.

Opposed to the inner ball race D is the outer ball race D¹. Between the two ball races are positioned, in operative contact with the races, a plurality of balls or rolling members D². For purpose of illustration I show a single series of balls, it being understood that while I prefer to employ balls I do not wish to be limited, except so far as I limit myself by the language of my claims, to these particular rolling members or to this particular disposition thereof. D³ generally indicates a sleeve rotatable about the cylindrical exterior of the sleeve C¹ and includes an extension D⁴ which may be forked or recessed or notched as at D⁵ to receive the balls D². The member D³ is shown as confined, on the shaft C⁴, between the washers C⁶ at one end and the washer or washers D⁶ at the other, these washers being positioned by the collar D³ and the head C⁵ respectively. The sleeve D³ is provided with a recess or cavity D⁷ intermediate its ends, which is closed for example by the screw member D⁸. It will be understood that any suitable lubricant for example grease may be inserted in the cavity D⁷ to lubricate the opposed bearing surfaces of the sleeves C¹ and D³. The washers C⁶

and D⁶ are preferably of copper material to confine or prevent the escape of the lubricant from between the opposed bearing surfaces.

Associated with the outer ball race D¹ is a 5 housing structure generally indicated as E. It is provided with a seat E¹ to receive the outer ball race D¹ and is clamped in position thereon for example by engagement with the member E² which is drawn against the member E as by the screws or bolts E³. The member E² is provided with the inward extension E⁴ within which is any suitable washer or packing means E⁵ confined as by the ring or angle E⁶. The member E has screwthreaded 10 into it the axially located hub member E⁷ which is axially apertured as at E⁸ to receive the compression spring E⁹ which exerts a thrust against the single ball E¹⁰ positioned in the recess C¹⁰ of the member C⁶.

20 Positioned on the hub E⁹ are the fan members G and positioned on the sleeve D³ are the fan members G¹. It will be understood that these fan members are of opposite pitch, since they rotate in opposite directions.

25 It will be realized that whereas I have described and shown a practical and operative device, nevertheless many changes might be made in the size, shape, number and disposition of parts without departing from the 30 spirit of my invention. I therefore wish my description and drawings to be taken as in a broad sense illustrative and diagrammatic rather than as limiting me to my specific showing.

35 The use and operation of my invention are as follows:

For many purposes, for example, for maintaining a circulation of air in a domestic hot air heating plant, it is desirable to employ 40 a fan positioned within a duct or confined space. I prefer to employ a duplex fan in which two fan elements or two sets of fan elements, of opposite pitch, are simultaneously rotated in opposite directions. The result is an increased efficiency or delivery of 45 air through a duct of given diameter, as compared to the air delivery of a single fan operating at like speeds of rotation. Owing to the employment of two sets of blades which 50 supplement each other, a breeze is created, the penetration of which, for a given power output is greater than in the prior art form of fan in which a single rotating member or set of blades is employed. Owing to the employment of two sets of blades, the speed of 55 the motor, for a given delivery of air, can be greatly reduced. Each set may be driven at, say, half the number of rotations per minute of the ordinary fan by employing a single 60 set of blades. The reduction in the speed of the motor and the reduction in the speed of rotation of the fan members thus result in a very quiet operation. A greater delivery of air is produced by a fan of given diameter 65 and a spiral effect, which is a limiting factor

in the simple disc or single fan set type is eliminated.

Referring specifically to the details of the present form it has for one advantage that the two fan elements and the power transmission therefor can be fastened directly to a motor shaft and no additional abutments or connections are necessary. This is a great advantage in setting up such a fan for use in an air or gas duct, as shown in Figure 1. 70 The principle of driving the fan elements simultaneously in both directions has great advantage over positive drive through gear or belt. The ball bearing serves as a planetary transmission, rotation in one direction 75 being maintained from the gauge or ball retainer, the member D³ D⁴, and rotation in the opposite direction being taken from the outer race, through the member E. The inner race is the driving member, rotating in unison 80 with the shaft C. The sleeve D³ rotates about the shaft C, and in a like direction of rotation. The extension D⁴ serves as the ball retainer. The ball E¹⁰, thrust by the spring E⁹, serves to keep the balls and races in firm contact, 85 preventing slippage. Whereas I have described and shown this improved transmission in connection with a duplex fan it will be realized that other applications thereof or uses therefor are available. 90

It will be understood that whereas I have shown bearing balls or spheres and a single series of them, I wish my claims to be understood as covering also the employment of such equivalents as rollers or as multiple 100 series of ball, except so far as the claims are specifically limited by their language.

I claim:

1. In a power transmitting mechanism adapted to drive fans in opposite rotational directions, a motor and a motor shaft, an extension sleeve mounted on said shaft, an inner race mounted on said extension sleeve, an outer race opposed thereto, rollers interposed therebetween, a rotatable retainer for said rollers, said retainer including a portion rotatable about said extension sleeve, a work performing element connected with said retainer and a work performing element connected with said outer race. 105

2. The structure of claim 1 characterized by the employment of a housing adapted to surround the rollers and the races therefor, the work performing element associated with the outer race being secured to said housing, 110 said housing being secured in relation to the outer race. 120

3. The structure of claim 1 characterized by the provision of a lubricant container associated with said retainer. 125

4. In a power transmitting mechanism adapted to drive fans in opposite rotational directions, a motor and a motor shaft, an extension sleeve mounted on said shaft, an inner race mounted on said extension sleeve, 130

an outer race opposed thereto, rollers interposed therebetween, a rotatable retainer for said rollers, said retainer including a portion rotatable about said extension sleeve, a work performing element connected with said retainer, a housing structure connected with the outer race, and means connected therewith for holding rollers and races in firm contact.

Signed at St. Louis, State of Missouri,
this 1st day of August, 1929.

LAURENCE M. PERSONS.
